A. F. DIXON

APPARATUS FOR ORIENTING GEOLOGICAL SPECIMENS IN BORE HOLES

Filed Sept. 19, 1924

By Henry J. Lucke, Attorney for Inventor:
A. F. Dixon, Inventor,
his ATTORNEY:

UNITED STATES PATENT OFFICE.

ABNER FAISON DIXON, OF NEW YORK, N. Y., ASSIGNOR OF ONE-THIRD TO THOMAS C. BANNON AND ONE-THIRD TO DONALD UPHAM, BOTH OF NEW YORK, N. Y.

APPARATUS FOR ORIENTING GEOLOGICAL SPECIMENS IN BORE HOLES.

Application filed September 19, 1924. Serial No. 738,602.

This invention relates to apparatus for orienting or ascertaining the azimuth position of rock specimens in bore-holes, in order that when a specimen is brought to 5 the surface its strata may reveal the direction of the dip.

The apparatus includes a rock penetrating tool which is lowered into the bore hole, and marks or indents the rock at the bottom of 10 the hole, in a position eccentric in relation to the axis of a core which will subsequently be drilled out by another apparatus. Together with this tool there is lowered into the hole an index sheet or card, which is 15 rotatable in relation to the tool holder, but whose position in azimuth is controlled by a compass device. Another part of the apparatus is a device for marking the index sheet, and this sheet marking device, or the 20 path in which it moves, is in fixed positional relation to the tool holder.

About the time the tool engages the rock, or after it has engaged the rock, the sheet marking device makes a mark on the sheet, 25 whose position in azimuth, controlled by the compass, is unaffected, or nearly unaffected, by rotation of the apparatus about its own axis, that is to say, by such rotation as may arise, for example, from twisting of the 30 cable during the lowering of the apparatus into the bore-hole. The marking device, however, does take part in such rotation, together with the tool-holder. Hence by correlating the position of the mark on the 35 sheet with the position of the mark made on the rock by the tool, the original azimuth position of the specimen in the ground can be ascertained.

For the compass device I prefer to use a 40 gyro-compass, which may be mounted in a chamber or compartment of a casing containing the tool holder and tool actuating mechanism. Alternatively, I may use a master gyro-compass which is retained on 45 the surface of the earth, and connect the same by wires to what is called a repeater motor, lowered into the bore hole together with the index sheet, sheet marking device and tool.

50 In the accompanying drawings there are shown, by way of example, two appliances embodying my invention, in Figs. 1 and 2 respectively, each of these figures being a vertical section showing one form of construction.

Referring first to Fig. 1, the apparatus therein shown comprises a cylindrical casing, which has a shackle at the top, for suspending it from a cable, and the casing is made in two parts, marked A and B respectively. The part A is the compass chamber, and is closed at the bottom by the part B, which may be called the tool-holder and is screwed to the rim of the part A, making a water-tight joint. The compass 60 C is gyroscopic, and is supplied with electric current by means of wires w which pass down through the cable. The gyro-compass C is suspended to rotate freely in the chamber A, and carries a sheet or card S, below 65 which there is mounted, on top of the compartment or chamber B, a marking device M, actuatable by an electromagnet E, so that when the magnet is momentarily energized by a brief current impulse the marker 70 is rocked and pricks the sheet S. The circuit x of the electromagnet is closed, when required, by a switch s in the chamber B, as will be described hereinafter.

Within the chamber B there is an elec- 80 tromotor P, supplied with current by means of wires y, which pass down through the cable, the circuit being closed by means of a switch s₁, as will be described hereinafter.

By means of a train of gearing G the motor 85 P drives a drill D, disposed eccentrically of the casing, and projecting from the bottom of the chamber B. The drill is axially movable within limits, in relation to the casing, being connected by a feather and groove F with the last member of the gear train. Upon the shank of the drill there 90 are two collars U and V. When the apparatus is lowered into the bore hole, and the point of the drill strikes the bottom, the 95 drill is pushed upwards in relation to the casing and the collar U closes the motor switch s₁, so that the motor is started, and drives the drill. Shortly thereafter the collar V closes the switch s in the circuit of 100 the electromagnet E, whereby the marker M is caused to prick the sheet S. The collar U keeps the motor switch s₁ closed till the hoisting of the apparatus allows the drill 105 to drop again, but the closing of the marker switch s by the collar V is only momentary, as the collar merely trips the lower switch arm in the course of the upward movement of the drill shank.

As the apparatus will usually work under 110

water at fairly high pressure, and it would be inconvenient to pack the bearing of the drill shank so tightly as to resist influx of water, I dispense with such water-tight 5 packing, and contemplate that the chamber B will generally be flooded with water while the apparatus is at work, unless I fill this chamber with oil, glycerine or the like. In order to prevent in any case access of water 10 to the switches s and s_1 I have in the example shown in Fig. 1 placed these switches in a small box O in the chamber B, and I fill this box with oil.

It will be apparent that the circuit from 15 the switches s and s_1 may be electrically connected with the electro-magnet E and the motor P through relays in the usual manner.

In the modification shown in Fig. 2 I have provided a gyro-compass casing with compartments A¹, B¹, a gyro-compass C¹, index sheet S¹, motor P¹, driving G¹ and drill D¹, all substantially similar to corresponding parts described with reference to Fig. 1, but the sheet marking device M¹ which I use in 20 this modification is a stylus mounted on a carriage, which is moved along a track M² by a chain M³, the chain being actuated by a drum M⁴ driven by a clockwork Z, whereby 25 the action of the sheet marking device M¹ can be timed. In the example shown I use the clock also to close, by means of an arm Z¹, a switch Z² in the motor circuit, though I may alternatively start and stop the motor by means of a switch at the surface of the 30 earth. The track M¹ has a horizontal portion parallel with a radius of the index sheet S¹, and while the stylus carriage is travelling on this horizontal part of the track the stylus marks the sheet. The said horizontal 35 part of the track is approached at its inner end by a sloping portion, up which the carriage is drawn by the chain M³ when the clockwork begins to rotate the drum M⁴, and at the outer end of the track there is a downward slope, whereby the carriage is caused 40 to remove the stylus from contact with the index sheet when the marking action is completed.

Before the apparatus is lowered into the 45 ground the clockwork is wound up and set so that it will close the motor switch Z² after a predetermined interval of time, and then impart rotation to the drum M⁴, whereby the stylus carriage is moved. The time 50 interval is pre-determined according to the depth of the hole, the rate at which the apparatus will be lowered, and whatever other conditions of time may be relevant.

The action of the apparatus will readily 55 be understood from the foregoing description.

When the apparatus reaches the bottom of the hole the motor is started, and the tool makes an indentation in the rock. This indentation may be in any azimuth position,

depending on the oscillation or twist to which the cable has been subjected during the lowering operation. After the tool has engaged the rock, and thus determined the position in which the indentation is made, 70 the sheet marking device comes into operation, and marks the index sheet. The position of the marking device is governed by the position of the tool, but the position of the sheet is independent thereof, being governed by the compass. After the marking of the rock and the sheet the apparatus is hoisted to the surface, and a coring apparatus is lowered into the hole. This apparatus drills out a core or specimen, which 80 bears the indentation previously made in the rock by the marking tool, the said indentation being eccentric in relation to the axis of the core. Hence, when the core has been brought up, its original azimuth position in 85 the ground can readily be ascertained by correlating the position of the indentation with the position of the mark on the index sheet, and the direction of the dip in the locality under examination can be ascertained from the strata of the core.

What I claim as my invention and desire to secure by Letters Patent of the United States is:—

1. In apparatus for the purpose set forth 95 the combination of a rock indenting tool, a holder for said tool arranged to be lowered into a bore hole, a compass device connected with said tool holder and rotatable about a vertical axis in relation to said tool holder, an index sheet carrier whose azimuth position is governed by said compass device, and a device for marking an index sheet, said device being carried by said carrier, said sheet marking device being in fixed positional relation to said tool-holder.

2. In apparatus for the purpose set forth 100 the combination of a rock indenting tool, a holder and actuating mechanism for said tool arranged to be lowered into a bore hole, a compass device connected with said tool holder and rotatable about a vertical axis in relation to said tool-holder, an index sheet carrier whose azimuth position is governed by said compass device, and a device for marking an index sheet, said device being carried by said carrier, said sheet marking device being in fixed positional relation to said tool-holder.

3. In apparatus for the purpose set forth 105 the combination of a cylindrical casing arranged to be lowered into a bore hole, a rock indenting tool mounted in said casing and extending from the bottom thereof eccentrically in relation to the axis of said casing, a compass device in said casing, rotatable about the vertical axis thereof, an index sheet carrier whose azimuth position is governed by said compass device, and a device for marking an index sheet, said de- 110

vice being carried by said carrier, said sheet marking device being in fixed positional relation to said casing.

4. In apparatus for the purpose set forth
5 the combination of a cylindrical casing arranged to be lowered into a bore hole, a rock indenting tool mounted in said casing and extending from the bottom thereof eccentrically in relation to the axis of said casing,
10 a compass device in said casing, rotatable about the vertical axis thereof, an index sheet carrier whose azimuth position is governed by said compass device, and a device for marking an index sheet, said device being carried by said carrier, the path of said sheet marking device being in fixed positional relation to said casing.
5. In apparatus for the purpose set forth
- the combination of a rock penetrating tool, a holder for said tool arranged to be lowered into a bore hole, a compass device connected with said tool holder and rotatable about a vertical axis in relation to said tool-holder, an index sheet carrier whose azimuth position is governed by said compass device, a 25 device for marking an index sheet, said device being carried by said carrier, said sheet marking device being in fixed positional relation to said tool-holder, and means for actuating said sheet marking device while 30 said tool is engaged with rock at the bottom of a bore hole.

In witness whereof I have signed this specification.

ABNER FAISON DIXON.
